ROLL.

1,173,736.

Specification of Letters Patent. Patented Feb. 29, 1916.

Application filed January 7, 1915. Serial No. 1,035.

To all whom it may concern:

Be it known that I, EDWARD V. PHELPS, a citizen of the United States, and a resident of Nashua, county of Hillsborough, State of New Hampshire, (whcse post-office address is 31 Newbury street, Nashua, New Hampshire,) have invented an Improvement in Rolls, of which the following description, in connection with the accompanying drawings, is a specification, like characters on the drawings representing like parts.

This invention relates to improvements in rolls which may be used for various purposes, the roll shown in the illustrated embodiment of the invention being designed for use as a couch roll for paper making and pulp treating machinery. These rolls are commonly formed from a rigid or semi-rigid core with an applied surface in the form of a relatively yielding and more or less frictional material. In the construction of these rolls the surfacing is commonly applied by winding on the core a covering composed of one or more strips of suitable material. The material commonly used consists of a woven or other fabric applied to the core in the form of a strip wound thereon in successive helical convolutions to form a tight, compact fabric surface for the roll.

It is a common practice to wind on the strip with the assistance of a binding wire or other member, the fabric strip either being longitudinally slit to receive the binding wire or folded on itself so that its edges are directed outward, the surface of the roll being formed by a succession of fabric edges tightly wound and compressed upon the core.

I have found that a roll constructed by winding strips of material thereon, and particularly a roll where the fabric strips are wound with their edges outward, tends to lose its true cylindrical shape under use, or in some cases even before the roll is put to use. This appears to be due to the greater tension applied to and maintained in the outer periphery or edge portion of the strip when wound on the core. This tends to draw the outer edge of each strip closer to the core and to cause each strip to curl over, the effect being noticeable in the entire core in a tendency to shrink in diameter at certain points.

The present invention has for its object a winding strip for a roll and the roll itself

so constructed and arranged that the tendency to deform is corrected. This permits the roll when complete to retain its original, perfect, geometrical shape without deformation or any tendency thereto.

The invention will be best understood by reference to the following description when taken in connection with the accompanying illustration of one specific embodiment thereof, while its scope will be more particularly pointed out in the appended claims.

In the drawings: Figure 1 is a side elevation in partial section showing one end of a couch roll embodying one form of my invention; Fig. 2 is a sectional elevation showing the same roll as is illustrated in Fig. 1; Fig. 3 is a portion of a fabric winding strip employed in winding the couch roll shown in Fig. 1; Fig. 4 is a portion of the same winding strip with a binding wire applied thereto; and Fig. 5 shows a portion of the surface of the completed roll on an enlarged scale.

Referring to the drawings and to the illustrative embodiment of the invention therein shown, the core or body of the roll to which the surfacing is applied may be constructed in any desired manner. Herein it consists of the core 1 of wood or any other suitable material provided with the end plates 2 and having the central shaft 3. To the core are secured strips of lagging 4 extending longitudinally the same and giving the effect of a grooved core. This represents a conventional core construction which is submitted for illustrative purposes only.

To the described or any other suitable form of core there is applied a winding strip of any suitable form and material. As illustrative of one form of winding strip I have shown the strip 5 (Figs. 3 and 4) which herein is formed of a coarse fabric, preferably woven in character. The strip is formed of several fabric layers, herein six, stitched together by the double row of stitching indicated at 6. The fabric strip is applied to the core by folding it over (as indicated in Fig. 4) about a binding member 7 of any suitable character, herein in the form of a metallic wire. To permit the strip to fold readily about the wire and compact lengthwise the core, several of the strips (herein 4) are cut centrally at 8 and opposite the line of fold. This provides the effect of a scoring so that the strip folds

about the wire with the edges of the strip in smooth alinement and the sides of the strip being capable of compacting closely on the core. With the aid of the binding wire 5 the fabric strip can be applied evenly, firmly and compactly as represented in Figs. 1 and 5, so that the outer edges of the fabric form a compact, dense, cylindrical fabric surface. Staples 9 may be applied at intervals over 10 the binding wire to the strips to prevent the wire from slipping.

To prevent the deformation heretofore referred to, I relieve the circumferential tension to which each convolution of the 15 strip is subjected by the winding operation by making a series of incisions 10 or slits in each double edge of the winding strip, these incisions being sufficiently deep and following each other with sufficient frequency to relieve all tendency of the strip 20 to occupy anything but a true, radial position. These incisions or slits might be made in the individual layers before being stitched together or might be made in the edges of 25 the successive convolutions after they are wound upon the roll, but I find it more convenient to construct the strip as shown in Fig. 3 complete with the transverse slits 10 formed herein as well as the longitudinal 30 slit 8, so that the strip is all ready for winding on the roll.

Preferably a sufficient number of slits only is made to relieve the unequal tension of the inner and outer edges of the fabric so 35 that when the strip is wound tightly on the core a solid unbroken surface is presented, the position of the slits being scarcely or not at all visible.

While the transverse slits 10 might be arranged in the strips at right angles to the 40 length thereof, herein, and preferably, I cut them more or less obliquely. This offsets the slit in each layer of the strip from the slit in the next adjacent layer and assists in 45 making the surface of the core more compact.

It is to be understood that the invention is not limited in its application to the specific form or material of winding strip herein 50 shown, but that it has application to winding strips of other forms and construction.

While I have herein shown and described for purposes of illustration one embodiment 55 of the invention, it is to be understood that the same is not limited thereto, but that extensive deviations may be made therefrom without departing from the spirit of the invention.

60 Claims:

1. A roll comprising a core and a strip of covering material wound spirally about

said core, said strip having a series of transverse slits in its circumferential edge.

2. A roll comprising a core, a strip of 65 covering material wound spirally about said core, and a binding member wound in said strip, said strip having a series of transverse slits in its circumferential edge.

3. A roll having a core, a strip of covering material wound spirally about said core, said strip having a longitudinal slit and a binding member registering with said slit, said strip having also a series of transverse slits in its circumferential edge. 70

4. A roll having a core, a strip of covering material wound spirally around said core, said strip having a scoring on its under side lengthwise the same, a binding member registering with the scoring, said 80 strip being folded about said binding member to present its edges outwardly and a series of transverse slits in the circumferential edges of said strip.

5. A roll comprising a core, a covering 85 wrapped around said core and transverse scoring slits in the circumferential edges of said covering.

6. A roll comprising a core, a fabric covering wrapped around said core and transverse scoring slits in the circumferential 90 edges of said covering.

7. A roll comprising a core, a covering wrapped around the core and scoring incisions in the covering transversely the 95 same.

8. A roll comprising a core having a surface formed by the edges of successive fabric layers wrapped around the core and transverse scoring slits in the circumferential 100 edges of said fabric layers.

9. A roll comprising a core, a strip of covering material wound spirally about said core and a series of slits in the circumferential edge of said covering arranged 105 obliquely the length of the same.

10. A roll comprising a core, a strip of covering fabric wound spirally around the core, the outer circumferential edges of said fabric being longitudinally discontinuous to 110 relieve the circumferential tension therein.

11. A roll comprising a core, a covering wrapped under tension about said core, the outer circumferential edges of said fabric being longitudinally discontinuous to relieve the circumferential tension therein. 115

In testimony whereof, I have signed my name to this specification, in the presence of two subscribing witnesses.

EDWARD V. PHELPS.
